UNITED STATES PATENT OFFICE.

ALPHA LEPELMAN, OF GLENDALE, CALIFORNIA.

DESIGN FOR A DRESS.

60,249.

Specification for Design. Patented Jan. 17, 1922.

Application filed May 21, 1921. Serial No. 471,507. Term of patent 3½ years.

To all whom it may concern:

Be it known that I, ALPHA LEPELMAN, a citizen of the United States, residing at

Glendale, in the county of Los Angeles and

State of California, have invented a new,

original, and ornamental Design for a Dress, shown of which the following is a specification, reference being had to the accompanying drawing, forming part thereof.

Fig. 1 is a front elevation of a dress; and

Fig. 2 is a rear elevation of same, showing my new design.

I claim:

The ornamental design for a dress, as

ALPHA LEPELMAN.
